UNITED STATES PATENT OFFICE.

FREDERIC C. MORTON, OF CHELSEA, MASSACHUSETTS.

DESIGN FOR A VEHICLE BODY AND TOP.

SPECIFICATION forming part of Design No. 31,375, dated August 8, 1899.

Application filed June 26, 1899. Serial No. 721,965. Term of patent 14 years.

To all whom it may concern:

Be it known that I, FREDERIC C. MORTON, a citizen of the United States, residing in Chelsea, in the county of Suffolk and State of Massachusetts, have invented and produced a new and original Design for a Vehicle Body and Top, of which the following description, in connection with the accompanying drawings, is a specification, like letters on the drawings representing like parts.

The design relates to a vehicle body and top thereof; and it consists in a vehicle body and top distinguished by their peculiar shape, as will be hereinafter set forth and claimed.

Figure 1 is a side elevation of a vehicle body and top embodying this design; Fig. 2, a plan view of the vehicle body and top shown in Fig. 1, and Fig. 3 an end elevation of the vehicle body and top shown in Fig. 1 looking toward the left.

The leading and distinguishing feature of this invention consists in a vehicle body and top of the shape or configuration shown, and consists in a rectangular-shaped box or top a set diagonally with relation to the body *b* of the vehicle and from which posts *c* project downward to the body *b*.

I claim—

The design for a vehicle body and top herein shown and described.

In testimony whereof I have signed my name to this specification in the presence of two subscribing witnesses.

FREDERIC C. MORTON.

Witnesses:

JAS. H. CHURCHILL,
J. MURPHY.
